[57] CLAIM

The ornamental design for a coffee table, as shown and described.

DESCRIPTION

FIG. 1 is a perspective view of a coffee table showing
my new design;
FIG. 2 is a top plan view thereof;
FIG. 3 is a bottom plan view thereof;
FIG. 4 is a right side elevation view thereof, the left side being a mirror image thereof; and,
FIG. 5 is a front elevation view thereof, the rear elevation view being a mirror image thereof.

FIG. 1

FIG. 2

FIG. 3

FIG. 4

FIG. 5
